UNITED STATES PATENT OFFICE.

NORMAN H. GAY, OF LOS ANGELES, CALIFORNIA.

REFRIGERATING COIL SYSTEM.

Application filed May 18, 1927. Serial No. 192,242.

This invention relates to improvements in refrigerating systems, and more particularly to the construction of the refrigerating coils and their associated connections.

5 It has heretofore been proposed to employ refrigerating systems in which headers were employed, to which were connected a series of coils for taking the refrigerant liquid from the inlet header and passing it to the chamber to be cooled, and thereafter discharging the gas formed by the evaporation of the liquid into the outlet header. It has also been proposed to provide a circulation of the refrigerant from an accumulator through a 15 coil in the chamber to be cooled.

The present invention relates to improvements in such devices in which the coils are made of large internal section and inlet and outlet headers are provided in direct 20 communication with these coils and with each other, so that a free flow of the refrigerant occurs from the inlet header through the coil to the outlet header, and back to the inlet header; further, the coils themselves are 25 provided of simple U-shaped form, with substantially horizontal passes at top and bottom, so that there is substantially no obstruction to the flow, and the friction of the refrigerant in the coils itself is reduced to a 30 minimum. The headers are of large size and a level of liquid refrigerant is maintained at all times in the outlet header by the action of separating the gases and liquid refrigerant as such comes in from the several 35 refrigerating coils.

By the provision of this free circulation of liquid refrigerant through the headers and coils, with a minimum of friction, the construction is simplified, the strength of the 40 various parts is increased, and the employment of subheaders is avoided: the reduction of friction is of value in reducing the necessity of a friction head to overcome the friction through the coils, and in particular an 45 accumulator of large size is employed to connect the headers and is insulated so that substantially no heating from the exterior occurs therein, and the evaporation from the surface of the liquid refrigerant reduces the 50 temperature of the refrigerant liquid in the accumulator so that its specific gravity is at a maximum, while on the contrary the refrigerant within the refrigerant coils is warmed from the chamber in which the coils 55 are contained, and a part of this liquid re-

frigerant is converted to gas by evaporation, so that the contents of the respective refrigerating coils is at a minimum specific gravity by reason of the mixture of liquid and gas present therein, and by reason of the slightly higher temperature prevailing in the liquid refrigerant in these coils. The refrigerant in the coils is therefore more buoyant, and this difference in specific gravity is employed to effect the circulation through the coils and 60 headers.

In these ways, a very simple and effective system is produced, of very simple construction but of high efficiency; and with these and other objects in view as will appear in the 70 course of the following specification and claims, there is described hereinafter with reference to the accompanying drawings, one form of execution of the apparatus.

In these drawings:

Figure 1 is a vertical section through the accumulator, the headers and brine tank of a 75 system employed for manufacturing ice.

Fig. 2 is a vertical section taken at right angles to the showing of Fig. 1, through the 80 brine tank and headers, showing the form of the refrigerant coils.

In these drawings is illustrated a form of application of the system according to this invention, in which a liquid refrigerant is 85 maintained in a vertical accumulator having large side branches which form the inlet and outlet headers for the refrigerating coils, and these coils themselves are formed of large diameter and for free flow so that the liquid 90 passes in circulation from the accumulator through the inlet header, the refrigerating coil, the outlet header and back to the accumulator. Any liquid refrigerant which is evaporated in the refrigerating coil passes upward 95 in the respective coil and into the outlet header, in which and in the upper part of the accumulator it is thoroughly and clearly separated from the liquid refrigerant, and is permitted to return to the compressor for 100 recompression and condensation. A constant liquid level is therefore maintained in the coils and in the accumulator, and in place of providing a head of liquid above the refrigerating coils, the latter are made of large 105 diameter so that the flow therethrough occurs without friction, and permits the free upward movement of the refrigerant gas formed therein.

In Fig. 1, the accumulator 10 is an insu- 110

lated stand pipe which has its lower end located in a pit 11 adjacent the tank 12. At the lower end of the accumulator is provided a baffle 13 having a small passage around one edge thereof for the upward movement of the refrigerating liquid. At the bottom of the accumulator 10 is provided a pipe 14 having a valve 15 for removing the oil trapped at the bottom of the accumulator. The normal liquid level thereby maintained in the accumulator is at about the line L—L, and a gauge glass 16 is provided on the exterior of the accumulator for reading this level. At its upper end, the accumulator is provided with the baffle plates 17 for assisting in the separation of any remaining liquid from the refrigerant gas as it escapes to the pipe 18 which leads back to the compressor.

Projecting laterally from the accumulator just above the baffle plate 13 is the inlet header 19 which extends through the wall 20 of the brine tank 12 and passes across this brine tank. A similar outlet header 21 is likewise connected to the side of the accumulator 10, at about the determined liquid level for operation. The inlet header 19 and the outlet header 21 are each of very large diameter and permit a free flow of the liquid refrigerant with respect to the accumulator 10. A plurality of refrigerating coils 22, 23, 24, 25 are provided, four of these coils being shown at each partition of the brine tank 12 in the particular illustration, all four being located substantially in a plane and forming a partition within the brine tank 12 to form the compartments within which the ice cans may be located. As shown in Fig. 2, the ends of these tubes are connected, preferably by welding, to the respective headers, and pass from the header along the brine tank to the opposite end thereof, then bent upwardly and form a return pass which leads back to the other header. The passes of the respective coils may be very nearly horizontal, but preferably have a slight upward slope from the inlet to the outlet header for ease in clearing the refrigerant gas. It will particularly be noted that these coils are much larger than in the usual refrigerating system, and provide a free flow for the refrigerant liquid from the inlet to the outlet header.

The refrigerant liquid coming from the condenser and the plant passes through the inlet pipe 30 down through the top of the outlet header 21 and passes in a loop coil 31 which leads back to a riser pipe 32 leading to the three-way valve 33 from which it may pass through a cold liquid pipe 34 for other purposes, or may be led through the wall of the outlet 10 by a pipe 35 to the downcomer liquid line 36. It will be understood that the valve 33 acts also as an expansion valve and permits the reduction of pressure on the refrigerant liquid in its passage to the downcomer 36. This downcomer 36 passes

through the baffle plate 13 so that the cold liquid is led in a gentle stream into the oil trap formed beneath this baffle 13 within the accumulator 10, and in proportion as the refrigerant liquid above this baffle is evaporated, more of the liquid passes upward around the edge of the baffle. The upper end of the downcomer 36 is open, so that any gas formed in the downcomer is permitted free escape to the upper end of the accumulator 10.

The brine tank is provided with the usual deck 40 resting on the joists 41, and may be disposed in any suitable manner for the reception of the ice cans and other purposes. It will be understood that this brine tank may be provided with the usual circulating systems and supports for the respective coils 22, 23, 24, 25.

In operation, the operator permits the condensed liquid refrigerant from the pipe 30 to pass through the cooling loop 31 and back to the expansion valve 33 and thence to enter the accumulator and pass downward in the downcomer pipe 36 to form a pool in the bottom of the accumulator 10. As a part of the gas escapes in the downcomer pipe 36 and a further portion in the lower part of the accumulator 10, the oil still remaining in the refrigerant is chilled and settles to the bottom, and the liquid level of refrigerant in the accumulator 10 is permitted to rise until it reaches the line L—L. As the liquid passes into the inlet header 19 and into the respective refrigerating coils connected thereto, it rises in these coils, and since their exteriors are exposed to relatively higher temperatures, a part of the liquid refrigerant is evaporated therein, and causes a pumping or movement of the combined gaseous and liquid refrigerant within the respective refrigerant coil, so that this mixture of gas, foam and liquid passes into the outlet header 21 and thence into the accumulator 10. Most of the foam and liquid is separated in the outlet header, and a further separation is effected by the baffle plate 17 at the upper end of the accumulator, so that substantially refrigerant gas free from any liquid returns to the compressor through the pipe 18. The low temperature prevailing within the outlet header 21 is likewise availed of to cool further portions of the incoming condensed liquid on its way to the expansion valve 33: while the liquid refrigerant merely re-passes below the level L—L back into the accumulator and downward and into the inlet header 19 again. Since it is only necessary to make up the quantity of liquid which has evaporated in the refrigerating coils, it is apparent that the downward flow through the downcomer 19 may be gentle and does not provoke any stirring or agitation of the oil in the trap beneath the baffle 13. From time to time, this oil may be drawn off by opening the valve 15.

It is obvious that the invention is not

limited to the specific illustration set forth, but that it may be modified within the scope of the appended claims.

I claim:

5. 1. In a refrigerating system, an inlet header, an outlet header disposed substantially above said inlet header, a plurality of refrigerating coils connected to said headers, each of said coils being of relatively large 10 internal section and being of U-shape so as to afford free flow for the gaseous and liquid refrigerant therethrough between said headers, and means to separate gaseous and liquid refrigerant coming from the outlet 15 header and to return the liquid refrigerant to the inlet header whereby a circulation of liquid refrigerant is established through said headers, coils and means by the difference in specific gravity between the liquid refrigerant in said means and the mixed gaseous 20 and liquid refrigerant in said coils.
2. In a refrigerating system, an accumulator, an inlet header, an outlet header disposed substantially above said inlet header, 25 said headers and accumulator being in free communication, and a plurality of refrigerating coils connected to said headers, each of said coils being of relatively large internal diameter and being of U-shape, whereby a free 30 and substantially unobstructed circulation is afforded for said liquid refrigerant through said accumulator, headers and coils, and whereby such circulation is established by the difference in specific gravity of the liquid refrigerant in said accumulator and that of the 35 gaseous and liquid refrigerant in said coils.
3. In a refrigerating system, a brine tank, a vertically disposed accumulator located external to said brine tank and having inlet and 40 outlet headers extending horizontally therewith from at different levels and passing into said brine tank, and a plurality of refrigerating coils located in respective vertical planes and joining said inlet and outlet headers, all of 45 said coils being of large diameter to afford unobstructed flow to the refrigerant so that a direct circulation is established from the accumulator through the inlet header, a respective refrigerating coil and the outlet header 50 back to the accumulator.
4. In a refrigerating system, a vertically disposed accumulator having horizontally extending inlet and outlet headers communicating directly therewith, and a plurality of refrigerating coils connecting said inlet and 55 outlet headers, so that a common liquid level may be established in said outlet header and accumulator for the free circulation of liquid downward through said accumulator, outward through the inlet header, upward through said coils, and back through said outlet header to said accumulator.
5. In a refrigerating system, a vertically disposed accumulator having horizontally 60 extending inlet and outlet headers communi- cating directly therewith, a plurality of refrigerating coils connecting said inlet and outlet headers, so that a liquid level may be established in said outlet header and accumulator for the free circulation of liquid through 70 said accumulator, headers and coils, a liquid refrigerant supply pipe including a coil located in said outlet header, a downcomer pipe located within said accumulator, and a connection including an expansion valve between 75 said liquid refrigerant supply pipe and said downcomer above the liquid level in said accumulator.
6. In a refrigerating system, a vertically arranged accumulator having a baffle near its bottom defining an oil trap chamber at the lower end thereof, a horizontal inlet header communicating for its whole area of internal section with said accumulator above the baffle, an outlet header communicating for its whole 80 area of internal section with said accumulator at a point above said inlet header, a plurality of individual refrigerating coils connecting said headers, a downcomer pipe within said accumulator and passing through said 85 baffle and extending above said outlet header, and a liquid supply line and expansion valve connected to said downcomer pipe at a point above said outlet header whereby a circuit of refrigerant liquid may be established in said 90 headers and a coil and the accumulator above said baffle.
7. In a refrigerating system, a refrigerating chamber, inlet and outlet headers located in said chamber at the same end thereof, a plurality of refrigerating coils of relatively large 95 internal section connecting said headers and extending from one end of said chamber to the other and back with single passes in each direction, and an accumulator connecting said 100 headers for free circulation therethrough, said accumulator having a gas withdrawing conduit connected thereto so that a free circulation of liquid refrigerant occurs from the accumulator through the inlet header, the said 105 coils, and said outlet header back to the accumulator, while the evaporation of liquid refrigerant in a respective coil produces a mixture of liquid and gaseous refrigerant of lesser specific gravity than the liquid in the said 110 accumulator whereby the free circulation is established.
8. In a refrigerating system, a vertical accumulator having horizontal inlet and outlet headers secured thereto with the latter above 115 the former and in free communication therewith, a baffle plate substantially partitioning said accumulator below said inlet header, a downcomer communicating with said accumulator below said baffle and above 120 said outlet header, and a conduit to deliver refrigerating liquid to said downcomer.
9. In a refrigerating system, an accumulator, an inlet header, an outlet header disposed substantially above said inlet header, said 125

headers and accumulator being in free communication, and a plurality of refrigerating coils connected to said headers, each of said coils being of relatively large internal diameter and being of U-shape, whereby a free and substantially unobstructed circulation will be caused by the difference in specific gravity between the mixed liquid and gas in the refrigerating coils and the liquid in the accumulator, 10 said circulation being continuous through the coils, outlet header, accumulator, inlet header, and back through the coils.

10. In a refrigerating system, an accumulator, an inlet header, an outlet header disposed at a level above said inlet header, said header and accumulator being in free communication, a plurality of refrigerating coils of large internal diameter and short length connecting said headers, and a brine tank containing said header and coils, said accumulator being located outside said brine tank so that it is not heated by the brine; said coils, header and accumulator being adapted to have a head of refrigerating liquid therein so that 25 a free circulation of liquid refrigerant is provoked by the difference in specific gravity by the refrigerating medium in the accumulator and the refrigerating medium in the said coils.

11. In a refrigerating system, a vertical 30 accumulator having horizontal inlet and outlet headers secured thereto with the latter above the former and in free communication therewith through the accumulator, a baffle plate substantially partitioning said accumulator below said inlet header whereby to form a chamber of quiescence for incoming refrigerant liquid, a conduit for incoming liquid refrigerant open to said accumulator below said baffle, and refrigerating coils connecting said inlet and outlet headers, whereby a liquid level of refrigerant may be established in said accumulator and coils and in said outlet header whereby the lesser specific gravity of the gas and liquid refrigerant in 45 said coils will establish a free circulation of liquid refrigerant through the coils, headers and accumulator, and whereby the incoming liquid refrigerant to replace the evaporated refrigerant in said circulation is maintained 50 in said chamber of quiescence whereby the oil contained therein is separated, and the liquid refrigerant itself alone enters into the circulation.

12. In a refrigerating system, a vertical 55 accumulator having horizontal inlet and outlet headers secured thereto with the latter above the former, refrigerating coils establishing free communication between said inlet and outlet headers, an admission conduit for liquid refrigerant including a cooling pipe at the bottom of the outlet header and a discharge opening into said accumulator near the bottom thereof, a baffle plate substantially partitioning said accumulator between said 60 inlet header and said discharge, and means

for removing gaseous refrigerant from the incoming liquid refrigerant before it enters the lower chamber in said accumulator defined by said baffle plate.

13. The method of operating a refrigerating system which comprises providing a circulation for liquid refrigerant upwardly through coils in the brine tank and downwardly through an accumulator, separating the gaseous from the liquid refrigerant in 75 said accumulator whereby the head in said accumulator comprises substantially gaseous refrigerant, and causing the difference in specific gravity between said liquid refrigerant in the accumulator and the mixed gases and 80 refrigerant in said coils to provoke a continuous circulation through the system.

14. In a refrigerating system, a vertical accumulator having horizontal inlet and outlet headers secured thereto with the latter above the former, refrigerating coils establishing free communication between said inlet and outlet headers, means to admit incoming liquid refrigerant to the bottom of said accumulator, and a cooling conduit for said 90 incoming liquid refrigerant in the bottom of said outlet header, said outlet header and accumulator being adapted to have a liquid level of refrigerant established intermediate the height of said outlet header whereby a 95 continuous circulation of liquid refrigerant may occur through said coils, headers and accumulator.

15. The art of refrigerating a container which comprises establishing a circuit of a 100 liquefied refrigerant medium through a low pressure system having ascending and descending legs, of which the ascending leg is located in the container, causing the heat of the contents of the container to evaporate 105 a part of said liquefied refrigerant in said ascending leg and thereby decrease the specific gravity of the refrigerant in said ascending leg, employing the difference in specific 110 gravities of the refrigerant in the ascending and descending legs to provoke a circulation of said liquefied refrigerant as such through the system, and removing the gaseous refrigerant as said liquefied refrigerant passes to said descending leg.

16. In the art of refrigerating a container as set forth in claim 15, the further step of replenishing the liquefied refrigerant evaporated from said circuit by introducing further liquefied refrigerant between said descending and ascending legs.

17. In a refrigerating system, an accumulator having a header in free communication therewith and through which refrigerant can return to said accumulator, a refrigerating coil connected to said header to deliver refrigerant thereto, said accumulator and header being adapted to have a liquid level of refrigerant maintained in said header, a 125 cooling pipe located in said header below said 130

maintained liquid level, means to deliver condensed refrigerant to said cooling pipes, an expansion valve connected to the top end of said cooling pipe, and a conduit leading 5 from said expansion valve into said accumulator.

18. In a refrigerating system as in claim 17, in which said conduit has openings into said accumulator above and below the main- 10 tained liquid level therein, so that incoming gas and liquid refrigerant may respectively be delivered above and below said liquid level.

19. In a refrigerating system, an accumu- 15 lator having horizontal inlet and outlet headers secured thereto and in free communication therewith, a refrigerating coil establishing communication between said inlet and

outlet headers, said accumulator, headers and coil being adapted to have a liquid level main- 20 tained therein intermediate the height of said outlet header, a cooling pipe for condensed refrigerant located in said outlet header below the maintained liquid level, and an ex- 25 pansion valve and conduit connecting the discharge end of said cooling pipe with said ac- cumulator.

20. In a refrigerating system as in claim 19, in which the cooling pipe ends are located outside of the header walls and the one end of 30 said conduit is located outside the wall of said accumulator, so that the expansion valve is located outside the header and aecumulator for access and adjustment.

In testimony whereof, I affix my signature.
NORMAN H. GAY.
